MOUNTING FOR DOORKNOBS OR HANDLES

Glenn E. Wertz, Rockford, Ill.

Application October 24, 1938, Serial No. 236,706

4 Claims. (Cl. 292—354)

This invention relates to mountings for door knobs or handles on latch operating bars, and has for the primary object the provision of a device of this character which will eliminate the use of screws or like fasteners now employed for securing the knob or handle on the bar and which will provide a construction that will permit a knob or handle to be easily pushed in place on the bar and automatically become secured thereon until manually released which may be easily and quickly brought about when desired.

With these and other objects in view, the invention consists in certain novel features of construction, combination and arrangement of parts to be hereinafter more fully described and claimed.

For a complete understanding of my invention, reference is to be had to the following description and accompanying drawing, in which

20 Figure 1 is a vertical sectional view, partly in elevation, showing mountings employed for the securing of a door handle or door knob on a latch operating bar and constructed in accordance with my invention.

25 Figure 2 is a transverse sectional view taken on the line 2—2 of Figure 1.

Figure 3 is a fragmentary perspective view illustrating one end portion of the latch operating bar.

30 Figure 4 is a perspective view illustrating a combined retaining clip and spring.

Figure 5 is a perspective view illustrating a core.

Figure 6 is a top plan view illustrating the core with a dog mounted therein.

35 Figure 7 is a perspective view illustrating the dog.

Figure 8 is a transverse sectional view illustrating one of several shapes in cross section that the operating bar may take.

40 Figure 9 is a view similar to Figure 8 showing another shape of the operating bar with the bore of the core shaped accordingly.

Figure 10 is a view similar to Figures 8 and 9 showing another shape in cross section of the operating bar and the bore of the core shaped to match therewith.

Referring in detail to the drawing, the numeral 5 indicates a fragmentary portion of a door and 6 a latch operating bar. It has been customary 50 to detachably secure on the bar 6 door knobs or handles through the use of set screws and other similar fasteners which have proven unsatisfactory due to the working loose of such fasteners and freeing the door knob or handle. The purpose of the present invention is to eliminate the

use of such fasteners and in Figure 1 is shown the present invention detachably mounting on the operating bar 6 a door knob 7 and a handle 8 both of which are equipped with chambers 9 in which are mounted cores 10. The mouths of the chambers are partly closed by inwardly directed flanges 11 for retaining the cores in the chambers 9. It is preferable that projections or teeth be formed on the inner faces of the flanges to engage in notches in the ends of the cores for securing the cores against rotation with respect to the door knob and handle. However, other means may be provided to bring the securing of the cores against rotation in the chambers. It is further understood that the cores are first positioned in the chambers of the handle and knob prior to the formation or bending of the flanges into the core retaining positions as shown in Figure 1.

The operating bar 6 includes angularly related faces and the cores 10 have bores 12 to receive the end portions of the operating bar, the shape of the bores of the cores matching the cross sectional shapes of the operating bar. The operating bar may be made of various cross sectional shapes as shown in Figures 8, 9 and 10 or of rectangular shape in cross section as suggested in Figures 1 and 5, that is in Figure 5 the bore of the core is shown of rectangular shape, consequently the bar used in connection therewith will be of a corresponding shape in cross section.

Each core 10 is of the same construction and reference to one specifically is thought sufficient for both. The core 10 is provided with a slot 13 communicating with the bore and opening outwardly through a side of the core and also extending from end to end thereof. The core substantially intermediate its ends is provided with notches 14 which communicate with the slot 13 and form seats or rests for a dog 15. The core 10 is further provided with an annular groove 16 communicating with the notches 14 in which is mounted a split spring clip 17 having integral therewith a spring finger 18 adapted to bear on the dog 15 for urging the latching end 19 of the dog into engagement with a notch 20 formed in the latch operating bar. The dog has formed thereon oppositely extending beveled lugs 21 adapted to rest in the notches so that the dog may have pivotal movement. It is to be understood that after the lugs 21 have been positioned 50 in the notches 14 with the dog lying in the slot 13 the split spring clip 17 is placed in the annular groove 16 to overlie the dog and retain the same within the slot 13 for pivotal movement. The non-latch end of the dog 15 is in the 55

- form of a beveled extension or portion 22 normally overlying an opening 23 formed in the knob or handle so that an instrument indicated by the character 24' may be inserted in the chamber and against the portion 22 for rocking the dog 15 on its pivot against the action of the spring finger 18 to disengage the latch end 19 of said dog from the notch 20 of the latch operating bar to free the knob or handle therefrom.
- 5 The ends of the latch operating bar are beveled, as shown at 24, the purpose of which is to permit said end to readily enter the bores of the barrels when the handles or knobs are pushed onto the latch operating bar and also to force
- 10 the latch ends 19 of the dogs downwardly into the slots 13 so that the cores may readily slip onto the latch operating bar until the ends 19 of the dogs move into the notches 20 thereby automatically locking the knob and handle on the
- 15 latch operating bar. Therefore, it will be seen that all screws and similar fasteners are entirely eliminated through the employment of the present invention and the latter permits a knob or handle to be readily pushed onto the latch operating bar and become automatically secured thereon and may be manually released through the use of a simple tool insertible in the opening of the knob or handle for moving the latch end 19 of the dog out of the notch of the bar.
- 20 30 It is believed that the foregoing description, when taken in connection with the drawing will fully set forth the construction and advantages of this invention to those skilled in the art to which such a device relates, so that further detailed description will not be required.
- 35 What I claim is:
1. In combination with a knob or handle having a chamber, a core mounted in said chamber against rotation and against withdrawal therefrom and having a bore provided with angularly related faces, a latch operating bar having angularly related faces and a beveled end to be received in the bore of the core and provided with a notch, said core having a slot communicating with the bore and opening outwardly through a side thereof, said core having notches in communication with the slot, a dog received in said slot and having a notch engaging end to engage in the notch of the bar, oppositely extending lugs formed on said dog and resting in said notches, and means for releasably securing the dog in the slot and acting as a tension means therefor.
- 40 45 50 55 60 2. In combination with a knob or handle having a chamber, a core mounted in said chamber against rotation and against withdrawal therefrom and having a bore provided with angularly related faces, a latch operating bar having angularly related faces and a beveled end to be received in the bore of the core and provided with a notch, said core having a slot communicating

with the bore and opening outwardly through a side thereof, said core having notches in communication with the slot, a dog received in said slot and having a notch engaging end to engage in the notch of the bar, oppositely extending lugs formed on said dog and resting in said notches, said core having an annular groove connecting with the notches, a split spring ring fitting in said groove and overlying the dog and the lug thereof to retain the lugs in the notches for pivotal movement.

3. In combination with a knob or handle having a chamber, a core mounted in said chamber against rotation and against withdrawal therefrom and having a bore provided with angularly related faces, a latch operating bar having angularly related faces and a beveled end to be received in the bore of the core and provided with a notch, said core having a slot communicating with the bore and opening outwardly through a side thereof, said core having notches in communication with the slot, a dog received in said slot and having a notch engaging end to engage in the notch of the bar, oppositely extending lugs formed on said dog and resting in said notches, said core having an annular groove connecting with the notches, a split spring ring fitting in said groove and overlying the dog and the lugs thereof to retain the lugs in the notches for pivotal movement, and including a spring finger to bear on the dog for urging the latter into engagement with the notch of the bar.

4. In combination with a knob or handle having a chamber, a core mounted in said chamber against rotation and against withdrawal therefrom and having a bore provided with angularly related faces, a latch operating bar having angularly related faces and a beveled end to be received in the bore of the core and provided with a notch, said core having a slot communicating with the bore and opening outwardly through a side thereof, said core having notches in communication with the slot, a dog received in said slot and having a notch engaging end to engage in the notch of the bar, oppositely extending lugs formed on said dog and resting in said notches, said core having an annular groove connecting with the notches, a split spring ring fitting in said groove and overlying the dog and the lugs thereof to retain the lugs in the notches for pivotal movement, and including a spring finger to bear on the dog for urging the latter into engagement with the notch of the bar, said dog having one of its ends beveled to form an extension, said handle and knob having an opening to permit a tool to be inserted therethrough for engagement with the extension of the dog for disengaging the latter from the notch of the bar.

GLENN E. WERTZ.
